UNITED STATES PATENT OFFICE.

CHARLES T. KUBICK, OF CHICAGO, ILLINOIS.

MOP-HEAD.

1,069,960.

Specification of Letters Patent. Patented Aug. 12, 1913.

Application filed March 10, 1913. Serial No. 753,817.

To all whom it may concern:

Be it known that I, CHARLES T. KUBICK, a citizen of the United States, residing at Edison Park, Chicago, in the county of Cook and State of Illinois, have invented 5 certain new and useful Improvements in Mop-Heads, of which the following is a specification.

This invention has for its object to 10 vide a novel and improved mop head which permits easy removal of the mop for washing or renewal.

The invention also has for its object to 15 provide a mop head which holds the mop rigidly at all times, and which is simple, strong and durable.

Other objects and advantages of the invention will be pointed out in the detailed description appearing hereinafter.

20 In the accompanying drawing forming a part of this specification, Figure 1 is a perspective view of the head with the mop attached, Fig. 2 is a plan view of the head with the mop removed, Fig. 3 is a cross section on the line 3—3 of Fig. 2.

Referring specifically to the drawing, the 25 mop head comprises two flat wooden segmental sections 5 and 6, respectively, to one of which is attached a handle 7, and the 30 other has a finger hold 8. The sections are nearly semicircular so that when they are assembled in spaced relation as shown, a substantially circular head is had which is encircled by the mop, the latter comprising 35 a band 9 carrying the mop fibers 10.

Between the sections 5 and 6 are interposed coiled springs 11 which tend to spread the same, and between the sections also extend guides 12 in the form of solid or tubular rods around which the springs are coiled. 40 The rods seat at one end in recesses 13 made in the inner straight edge of the section 5 in which recesses said rods are made fast by pins 14, these recesses being also large enough 45 to permit one end of the springs to enter the same, and the pins 14 also serving to secure said ends of the springs. The other ends of the rods work loosely in recesses 15

in the inner straight edge of the section 6 which is opposite to the straight edge of 50 the section 5. The corresponding ends of the springs also extend into the recesses 15 and are secured therein by pins 16.

The mop is put on the head by pressing 55 the sections 5 and 6 together so as to reduce the circumference of the head. The band 9 carrying the mop fibers 10 is now placed around the head so as to engage the curved edge thereof, and upon releasing the sections, they are spread by the springs 11 so 60 that the mop is now securely held in place on the head. The curved edges of the sections are made concave as shown in Fig. 3, so that they may obtain a better hold on the mop.

65 The mop can be quickly and easily put on or taken off, and it is therefore not necessary to put the head in water if the mop is to be washed. The mop is rigidly held, the springs 11 automatically adjusting the sections to the mop band 9. The springs also reduce the shock to furniture or other objects that may be struck by the mop when in use.

70 I claim:

1. A mop head comprising spaced sections 75 movable toward and from each other, springs between the sections for spreading the same, and a mop encircling the sections.

2. A mop head comprising spaced flat 80 segmental sections having their straight edges opposite each other, springs for spreading the sections, and a mop encircling the curved edge portions of the sections, said edge portions being concave.

85 3. A mop head comprising opposite expansible sections, and an annular mop encircling the edges of said sections and frictionally held thereon.

90 In testimony whereof I affix my signature in presence of two witnesses.

CHARLES T. KUBICK.
